UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,315,559.

Specification of Letters Patent. Patented Sept. 9, 1919.

Application filed December 7, 1916. Serial No. 135,563.

To all whom it may concern:

Be it known that I, ALFRED G. F. KUROWSKI, a subject of the Emperor of Germany, (but having taken out his first but not his final United States naturalization papers,) residing in Brooklyn Borough, in the county of Kings, city and State of New York, have invented certain new and useful Improvements in Type-Writing Machines, of which the following is a specification.

This invention relates to pressure or feed roll mechanism for coöperating with the platen to guide and feed work-members on the same. The invention further relates to a paper shield coöperating with the pressure or feed roll mechanism in guiding and feeding the work-members on the platen.

In the present improvement there are provided two series of aligned rolls connected together, so as to move as a unit into and out of engagement with the work-members on the platen. This unitary movement eliminates any tendency to buckle or disalign the work-sheet on the platen. The rolls extend through corresponding openings in a paper shield which envelops the lower side of the platen. This paper shield is made of stiff material for the greater part of its circumferential dimension, and then of flexible material for the remainder of its area, so as to form one continuous finger or holding edge which will tightly hug a work-sheet to the platen at the front of the same. This flexible strip is provided with a series of apertures which add to its flexibility and smoothening action on the work-sheet, and also permits the edge of the work-sheet to be visible as it comes around the platen, before it has actually protruded from between the shield and the platen. The connection between the rigid and flexible portions of the shield is made at a point and in a manner such that it will not catch on the edge of the work-sheet as it is positioned on the platen.

Other features and advantages will hereinafter appear.

In the accompanying drawings,

Figure 1 is a perspective view looking from below and in front, showing the rolls and shield in their active position in engagement with the platen, and is partly broken away to show the shifting mechanism.

Fig. 2 is a vertical section on line 2—2 of Fig. 6, showing the pressure or feed rolls and the shield in their depressed position such that a work-sheet may be admitted to a position between the platen and the guiding means.

Fig. 3 is a view similar to Fig. 2, except that parts have been restored to their normal position in intimate relation with the platen.

Fig. 4 is a vertical section from front to rear, showing the particular structure of the guiding means for the unitary pressure member, and also the mounting for one of the traveling rolls whereby the platen frame and carriage run along the shift rail.

Fig. 5 is a longitudinal section through one of the spiral springs which maintain the feed rolls in intimate contact with the platen.

Fig. 6 is a front contracted view in elevation, partly broken away to show the underlying structure of the shifting means for the feeding and guiding mechanism.

Fig. 7 is a contracted top plan view, with half of the platen and shield removed to show the underlying roll structure.

Fig. 8 is a top plan view of the feed rolls, a pair of the feed rolls being in cross-section to show their structure.

Fig. 9 is an end view, in elevation, of the paper shield detached, and showing one of its latches in its inactive and active positions, in full and dotted lines, respectively.

Fig. 10 is a fragmentary section taken from front to rear, showing the feed rolls as detached from their supporting brackets to disclose the arrangement of mounting the rolls in the brackets.

Fig. 11 is an enlarged vertical detail section, taken from front to rear, of the front portion of the paper shield, showing the manner of attaching the flexible strip to the stiff body portion thereof.

Referring more particularly to separate parts of this invention as embodied in the form shown in the drawings, 1 indicates the platen which is mounted in the usual manner, by means of shaft 2, in a platen frame 3. The platen may be rotated in the usual manner by a line-space-mechanism and a knob. 10 The platen frame includes side plates 4 connected at their lower ends by a cross beam 5, which is channeled to receive other mech-

anism and to give a light strong structure. The side plates 4 are also connected at their downwardly and forwardly sloping rear sides by an apron 6, whose particular structure will be more specifically described hereinafter.

In order to assist in guiding and feeding the work-sheet on the platen 1, there are provided two series of pressure or feed rolls 7 and 8; the former are the larger and engage somewhat to the rear of a vertical plane passing through the axis of the platen, while the latter are smaller and engage the platen considerably in front of the same vertical plane. These rolls are each composed of a spool 9 (Fig. 8), having a rubber covering or coating 10, so as to give a yielding, engaging and yet positive surface. The series of rolls 7 and 8 are rotatably mounted on shafts 11 and 12 respectively. In order to prevent the rolls from moving longitudinally of the shafts 11 and 12, there are provided suitable spacing collars 13 held themselves against axial movement by means of pins 14.

The rolls are so mounted that they will move as a unit toward and from the platen 1. To do this, the shafts 11 and 12 have reduced portions 15, which enable them to set into open-sided slots 16 and 17, (Fig. 10) in double-armed brackets 18. The brackets 18 are pivotally mounted at suitable intervals on a supporting rod 19. The two series of feed rolls are shown to be mounted to move as a unit, having a fixed relation with respect to each other.

Shifting of this unit as a whole is accomplished by providing on the supporting rod 19 at intervals thereon a series of forked arms 20 to which are pivotally connected cranks 21. Normally, the pressure or feed rolls 7 and 8 are held in intimate contact with the platen 1, by means of a series of spiral springs 23 loosely mounted on the shaft 22.

The particular structure of the spring mechanism will be seen by reference to Fig. 5. One end of spring 23 is in each instance connected to a collar 24 loose on the shaft 22 and having a pin or projection 25 engaging with set screw 26 on the corresponding arm 20 of the supporting rod 19. The other end of each spring 23 is secured to a collar or sleeve 27 loosely mounted on the shaft 22, but provided with a series of openings 28, into which may be inserted a stop or screw 29 arranged to engage limiting edges 20 provided on the cross beam 5. The action of these spring units is such that they will tend to swing the pins 25 upwardly, thereby tending to move from the position in Fig. 2 to the position in Fig. 3, forcing the feeding mechanism up into intimate engagement with the platen 1.

In order to depress the feed rolls out of

engagement with the platen, there is provided on the rock shaft 22 a crank 31 operated by a thrust link 32, in turn actuated by a bell crank 33 secured to a stub shaft 34, mounted on one of the sides 4 and having secured on its outer end a finger-piece 35. By depressing this finger-piece 35, the shaft 22 will be rotated, causing the cranks 21 fast thereon to pull down the joined feeding rolls against the tension of the springs 23, from the position indicated in Fig. 3 to the position indicated in Fig. 2. One arm of the bell crank 33 engages under the top strip of one of the sides 4 to limit the downward movement of the finger-piece. At this limit the connection of the other arm of the bell crank to the thrust link 32 will have to pass beyond the dead center so that parts will be locked, enabling the operative to have both hands free to insert the work-sheet.

For this purpose of guiding the movement of the unitary pressure mechanism, so as to be substantially vertical, the supporting rod 19 is arranged to slide vertically in a series of slots 36 formed in pairs of partitions 37 and 38, provided on the cross beam 5. The partitions 37 and 38 are located on opposite sides of the hubs of the two-armed brackets 18, so that they also limit the movement of the brackets 18 lengthwise of the supporting rod 19. The shaft 22 passes through the partitions 38, which, therefore, serve to steady the shaft, and, by bringing it within the channeled frame 5, prevents distortion of the whole platen frame by the tension of the springs 23. Each of the brackets is formed with a V-shaped tooth 39 located in one of the slots 36 and engaging the sides of the corresponding partition 38, so as to limit the extent of the swinging movement of the brackets about the rod 19, and thus limit the extent of canting of the feeding and pressure rolls as a unit.

To coöperate with the apron 6 and the rolls 7 and 8 in feeding and guiding the work-sheet around the platen 1, there is provided a paper shield 40, which is in the form of a distorted surface of a cylinder, enveloping, more or less closely at different points, the under side of the platen 1. The rear edge of the shield 40 is digitated or provided with a series of fingers 41, which mesh with alternating fingers 42, provided on the lower edge of the apron 6. The fingers 42 arch inwardly at 43 to throw the bottom edge of the work-sheet toward the platen as it is inserted. This prevents the work-sheet catching on the points of the fingers 41 which are covered by humps 43 in the fingers 42. The lower ends of the fingers 42 pass considerably beyond the fingers 41, so that they in turn will be in no danger of catching on the work-sheet. This form of connection between the apron 6

and the shield 40 permits a relative movement whereby the shield 40 can be caused to hug the platen closely in one instance when a work-sheet is in position, and can be separated widely from the platen in another instance (Fig. 2) to permit a new work-sheet to be inserted in position on the platen.

The movement of the shield 40 is controlled by the same means which control the movement of the pressure or feed rolls 7 and 8. In fact, the shield is supported by the shafts 11 and 12 as it rests on some of the collars 13, which may be enlarged relatively to others of the collars for this purpose. The shield is provided with suitable openings 44 and 45 through which the rolls 7 and 8 may project to engage the platen. The sides of these openings 44 and 45 are turned outwardly to avoid their catching on the edge of the work-sheet.

The shield is further supported by means of brackets 46, one at each end, having open bearings 47 engaging the supporting rod 19. Lengthwise movement of the shield is prevented by collars 48 engaging these brackets. The shield is locked in position by a pair of latches 49 pivotally mounted on the brackets 46 and shiftable from a position shown in full lines in Fig. 9 to the position shown in Fig. 1, to bar the open sides of the bearings 47. Each latch 49 is formed so as to be self-acting. The edge 50 thereof slopes radially nearer to the axis 51 of the latch, toward its outer end from the dip 52 of the latch, so that any tendency of the rod 19 to move out of the bearing 47 will merely cause the latch 49 to swing slightly and pinch the rod 19 more tightly against the edge 53 of the bearing.

The major portion 54 of the shield 40 is made of a rather stiff sheet metal, so as not to be easily bent or distorted and to hold its shape. The front of the shield 40, however, is formed of a flexible strip 55, so that it may be brought into actual engagement with the front side of the platen in order to aid in holding the work-sheet snug on the platen and properly guide the same. This really forms a holding finger for the work-sheet very little below the line of writing for the full length of the platen.

To add to the flexibility of the strip 55 and its smoothening action on the work-sheet, it is provided with a series of apertures 56 located at suitable intervals. These apertures also enable the operator to see the edge of the work-sheet as it is inserted on the platen, so as to determine whether it is properly aligned before the shield and pressure rolls are brought up to their engaging position with the platen. The connection of the flexible strip 55 to the major portion of the shield is made so that there

will be no tendency of the edge of the work-sheet to catch at the junction. The rear edge of the strip 55 overlaps and underlies the front edge of the major portion of the shield. Tabs 57 on the major portion 54 extend through openings 58 in the strip 55 and are bent backwardly (Fig. 11) to grip the strip 55 tightly.

The operation of the device will be readily understood when taken in connection with the above description. Ordinarily, the springs 23 hold both the pressure rolls 7 and 8 and the shield 40 in the position of Figs. 1 and 3 in intimate relation with the platen 1. This enables the rolls 7 and 8 to grip the work-sheet between their surfaces and the surface of the platen, so that by rotating the platen in any usual way, the work-sheet will be fed around to and past the line of writing. When it is desired to insert a fresh work-sheet on the platen, the finger-piece 35 is depressed from its Fig. 3 position to its Fig. 2 position, whereby the rock shaft 22 will be rotated, swinging down the cranks 21 so as to pull down the arms 20 against tension of the springs 23. This will depress the supporting rod 19, carrying down the two series of pressure rolls and the shield. If the finger-piece 35 is pressed down far enough, the toggle formed by the link 32 and the connected arm of the bell crank 33 will pass beyond a dead center (Fig. 2) and lock, permitting the operative to use both hands in inserting the work-sheet. The first edge of the work-sheet will be deflected by the bends 43, so as to escape the finger 41, and will come around to engage with the flexible strip 55 of the shield. The openings 56 enable the operator to determine whether the paper is properly positioned after it has been inserted. The finger-piece 35 can be returned to its raised position, enabling the springs 23 to force the shield 40 and the pressure rolls 7 and 8 up into their normal position, causing the pressure rolls to grip the work-sheet, and also causing the flexible strip 55 to hold the work-sheet snug on the platen adjacent to the line of writing.

Variations may be resorted to within the scope of the invention, and portions of the improvements may be used without others.

Having thus described my invention, I claim:

1. The combination with a platen frame, including a bottom channeled bar and a platen, of spaced feed rolls co-operating with said platen, a longitudinal shaft lying within said bar, springs encircling said shaft and normally maintaining said feed rolls in intermediate engagement with said platen, a finger-piece, and a connection from said finger-piece to said shaft to release said feed rolls, including a toggle capable of being thrown to a locked position just beyond the dead center, so as to maintain said feed rolls

out of engagement with said platen against the tension of said springs.

2. The combination with a platen frame, including a bottom channeled bar and a platen, of feed rolls circumferentially spaced with respect to said platen, a rigid frame for uniting said rolls to move as a unit, a crank shaft lying within said bar for shifting said frame, springs encircling said shaft for maintaining said frame in an upper position with said rolls in engagement with said platen, a toggle connected to said crank shaft, and a finger-piece for operating said toggle to release said feed rolls, said toggle being capable of being thrown beyond a dead center to lock said feed rolls out of engagement with said platen.

3. The combination with a platen frame, including a bottom channeled bar and a platen, of a supporting rod beneath said platen and lying within said bar, a series of brackets spaced at equal intervals along said rod, a shaft also lying within said bar, springs tensioned around said shaft and tending to raise the rod, a pair of shafts mounted in said brackets in transversely-spaced relation with respect to one another, and a series of rolls on each of said pair of shafts coöperating with said platen, said rolls being held in rigid spaced relation with respect to each other by said brackets.

4. The combination with a platen frame, including a bottom channeled bar and a platen, of rolls adapted to run upon the platen, a roll frame in which said rolls are journaled, partitions on said bar at a plurality of points along its length, a shaft journaled in said partitions for moving the rolls away from the platen, and springs coiled around said shaft, bearing against the bar and pressing the frame to hold the rolls upon the platen.

5. The combination with a platen frame, including a bottom channeled bar and a platen, of a supporting rod beneath said platen, guides spaced along said rod for directing vertical movements of said rod, brackets pivotally mounted on said rod and spaced at intervals, shafts mounted on said brackets, said brackets rigidly joining said shafts so as to prevent relative bodily movement, rolls rotatably mounted on said shaft and coöperating with said platen, a shaft lying within said bar and having arms underlying said rod, springs encircling said last-named shaft and anchored in said bar, for maintaining said supporting rod and said rolls in their uppermost position so that said rolls will coöperate with said platen, and manual means for depressing said rolls out of engagement with said platen against the tension of said springs.

6. The combination with a platen frame, including a bottom channeled bar and a platen, of two series of spaced rolls coöper-

ating with said platen, a unitary frame for rigidly joining said series of rolls, a rotary crank shaft lying within said bar and connected to reciprocate said unitary frame and said rolls vertically, springs encircling said shaft and anchored in said bar to raise the rolls, a linkage for oscillating said crank shaft against the springs, and a finger-piece for operating said linkage.

7. The combination with a platen frame, including a bottom channeled bar and a platen, of rolls adapted to run upon the platen, a roll frame in which said rolls are journaled, partitions on said bar at a plurality of points along its length, a shaft journaled in said partitions for moving the rolls away from the platen, rock arms revoluble on said shaft and bearing against the roll frame, and springs coiled around the shaft and bearing against the bar and the rock arms to hold the rolls upon the platen.

8. The combination with a platen frame, including a bottom channeled bar and a platen, of rolls adapted to run upon the platen, a roll frame in which said rolls are journaled, partitions on said bar at a plurality of points along its length, a supporting shaft journaled in the roll frame and comprising rock arms, a rock shaft journaled in said partitions and comprising rock arms connected to the first rock arms to enable the rocking of the rock shaft to withdraw the rolls from the platen, third rock arms journaled on the rock shaft and bearing against the supporting shaft, and springs coiled around the rock shaft, bearing against the bar and thrusting upon the third rock arms to carry the rolls against the platen.

9. The combination with a platen frame, including a bottom channeled bar and a platen, of two series of rolls coöperating with said platen, brackets for rigidly uniting said series of rolls to move as a unit, a supporting rod for said brackets, arms on said supporting rod, cranks connected to said arms, a rock shaft, lying within said bar, on which said cranks are mounted, rotatable to move said rolls out of engagement with said platen, springs encircling said shaft to hold the rolls against the platen, a crank on said rock shaft, a link connected to operate said last-mentioned crank, a bell crank for operating said link, and a finger-piece for operating said last-mentioned bell crank.

10. The combination with a platen frame, including a bottom channeled bar and a platen, of feed rolls coöperating with said platen, a shaft frame for said feed rolls, a rock shaft lying within said bar, springs encircling said shaft, means for overcoming the tension of said springs to withdraw said feed rolls out of engagement with said

platens, said springs being loosely mounted on said rock shaft and connected to act on said shift frame independently of said rock shaft, and a plate edge on said bar against which said springs bear.

11. The combination with a platen frame, including a bottom channeled bar and a platen, of a series of feed rolls coöperating with said platen, a shift frame for said feed rolls, a rock shaft journaled within said bar for controlling said shift frame, and springs loosely mounted on said rock shaft operating by engaging said frame and said shift frame at opposite ends.
15. 12. The combination with a platen frame, including a bottom channeled bar and a platen, of circumferentially-spaced feed rolls for said platen, a rigid frame for mov-

ing said feed rolls as a unit to and from said platen, partitions spaced along the channel of the bar, a rock shaft journaled in said partitions, arms extending from said shaft, and springs bearing against the bar and coiled around the shaft to lift the arms to carry the rolls against the platen.

13. The combination with a platen, of feed rolls for said platen, a supporting rod, brackets supporting said feed rolls on said supporting rod, a paper shield for said platen inserted on said rod, and a self-acting lock maintaining said shield on said rod.
